UNITED STATES PATENT OFFICE.

JAY S. STROUSE, OF BALTIMORE, MARYLAND, ASSIGNOR OF ONE-HALF TO CHARLES E. TRACE, OF BALTIMORE, MARYLAND.

CARBURETING APPARATUS FOR INTERNAL-COMBUSTION ENGINES.

1,091,600.

Specification of Letters Patent. Patented Mar. 31, 1914.

Application filed January 9, 1913. Serial No. 740,914.

To all whom it may concern:

Be it known that I, JAY S. STROUSE, a citizen of the United States, residing at Baltimore, Maryland, have invented certain improvements in Carbureting Apparatus for Internal-Combustion Engines, of which the following is a specification.

Owing to the present price of gasoline, the substitution of a heavier hydrocarbon such for instance, as kerosene as a fuel in an internal combustion engine, would have a decided advantage not only from a monetary point of view, but also from the fact that for a common volume of the two fluids, the kerosene would, with practically perfect combustion, develop more power than gasoline, a result due to the greater number of units of heat contained therein. But as kerosene requires a higher degree of heat for its vaporization, considerable difficulty is experienced in its practical use, and particularly in the act of starting the engine.

Various devices and apparatus have been constructed to obviate the difficulty above stated, and the present invention as herein-after described, is for that purpose.

In the description of the present invention which follows, reference is made to the accompanying drawing which is a sectional view of such parts of a carbureting apparatus for an internal combustion engine of an automobile, as are involved in the invention.

Referring now to the said drawing, 1 is a float chamber adapted to contain a hydrocarbon at a predetermined height or level which is maintained by means of a float 2 secured to the stem 3 the lower end of which is pointed to form a valve 4. The valve 4 controls a passage 5 communicating with a lower extension 9 of the float chamber, which extension is supplied with kerosene through a pipe the end only of which is shown and denoted by 7.

10 is a cock whereby water collecting in the extension 9 can be drawn off.

The float 2 is weighted to give it the desired flotation, by means of the weighted levers 12 fulcrumed to lugs on the bonnet of the float chamber, the shorter arms of which levers rest in a groove in the collar 14 which is susceptible of an up-and-down movement on the stem 3. The bonnet of the float

chamber is held in place by means of a plate spring 15 which is pivoted to any fixed part 55 of the apparatus.

At one side of the float chamber 1, and formed as a part thereof, is a shell 17 containing among other devices hereinafter described, the mixing chamber 19 having a water jacket 20. Water for heating purposes enters the water jacket 20 through the pipe 21, and escapes through the pipe 22. Below the lower end of the mixing chamber 19, the shell 17 is bored transversely, and in the cylindrical opening 26 thereby produced and with which the mixing chamber is in communication, is placed the valve which controls the admission of atmospheric air to the said chamber, but which valve, as its construction is well known, and forms no part of the present invention, is not shown.

24 is an open space extending laterally through the shell 17, and 25 an opening leading from the said space to the interior of the cylindrical valve opening 26, to admit air to the interior of the valve for admixture with the vapor of hydrocarbon introduced into the valve in a manner hereinafter described.

27 is a vertical tubular plug screwed into the material of the shell 17, the interior of which is in communication with that of the float chamber by means of the duct 29, in order that kerosene in the plug will rise to the level of that in the float chamber. The body of kerosene is denoted by 30.

31 is a horizontal passage in the material of the shell 17 having a vertical extension 32 the upper end of which is stopped by the tubular plug 33. The passage 31, its extension 32, and interior of the tubular plug 33, are all in communication with the float chamber through the medium of the aperture 34 in the wall of the tubular plug 27, and in consequence, there is a common level 95 of fluid throughout the apparatus when the engine is not in operation. The interior of the vertical tubular plug 33 is also in communication with the lower end of the mixing chamber 19, by means of the duct 35 100 which leads to an annular space 36 around the plug, and the hole 37 in its wall. To admit of the insertion of the plug 27, the shell 17 is bored, and provided with the screw stopper 39. The vertical extension 105 32 of the passage 31, at a point above the

level of the fluid, is open to the outer air through the lateral opening 40 the extremities of which are covered with gage disks.

The apparatus as above described is well known in the art, and forms no part of the present invention.

42 is a tubular shell which surrounds the upper portion of the tubular plug 27, having such internal diameter as to provide 10 an annular space 43 around the said plug, in which fluid rises to the common level; and around this device is placed the annular closed jacket 45 formed of some electric-insulating material, such as porcelain, in 15 which is placed an electrically heated coil 47 in contact with the tubular shell 42. The tubular shell 42 is preferably closed at its end, and provided with the lateral apertures 49 which serve to distribute the vapor 20 within the valve, and thereby facilitate its mixing with air entering the valve through the opening 25.

The primary function of the heating coil 47, is to vaporize a limited quantity of fluid 25 in the annular space 43 around the upper portion of the tubular plug 27, and adapt it to enter the valve which is supplied with air by means hereinbefore described, and also retain it in a combustible condition and 30 available at all times to start the engine by what is generally termed the "cranking" operation.

It will be understood that by heating the upper stratum of an annular body of kerosene of a limited transverse area, its vaporization can be easily accomplished by the employment of the heating coil 47, and that a hydrocarbon having a much greater density than gasolene can be substituted for the latter fluid, and the advantages arising for such substitution availed of.

It will be seen by reference to the drawing, that the heated jacket 45 extends considerably above the level of the hydrocarbon 45 in the plug 27, and the annular space which surrounds the same. This construction is for the purpose of heating the vapor arising from the fluid, and preventing to a certain degree, its condensation or return to a liquid form, a change to which it is particularly liable when a heavy body of hydrocarbon such as kerosene is used.

Supposing the engine to be at rest and the heated vapor arising from the kerosene in 55 the annular space 43 to be passing to the interior of the valve where it is mixed with the air, and the "cranking" operation to be commenced, the first upward stroke of the engine, causes the entire body of heated

vapor in the annular space 43 to be drawn 60 into the valve. At the same time a limited amount of fluid and vapor is drawn from the extension 32 of the passage 31 by means of the hollow plug 33 and the duct 35 which forms a means of communication between 65 its interior and the mixing chamber 19, with the result that there is immediately formed in the valve and the mixing chamber, an explosive mixture of vapor and air which upon being ignited by the sparking appliances, causes the initial operation of the 70 engine.

It will be understood that the starting operation just described is mainly due to the concentration of heat from the coil 47 upon 75 a limited quantity of fluid in the annular space 43, and the vapor arising therefrom, and the holding in reserve of a body of vapor which when the engine is motionless, is continuously passing into the valve, and 80 mixing with atmospheric air therein, thus establishing a condition which only requires a limited upward movement of the engine piston to effect the entrance of more air, to produce a mixture adapted for ignition to 85 effect the operation of the engine.

I claim as my invention:—

1. In a carbureting apparatus, the tubular plug which conveys hydrocarbon to the mixing chamber of the apparatus, combined with a tubular shell open at the top, which surrounds the plug, the said shell having an internal diameter greater than the exterior diameter of the plug, whereby an annular fluid-receiving and holding space around the 90 plug is produced, and an electrically heated coil which surrounds the said tubular shell, to conduct heat to the said shell and thence to the fluid within the said annular space.

2. In a carbureting apparatus, the tubular plug which conveys hydrocarbon fluid to the mixing chamber of the apparatus, combined with a tubular shell open at the top, which surrounds the plug, the said shell having an internal diameter greater than the exterior 100 diameter of the plug, whereby an annular fluid-receiving and holding space around the plug is produced; an electrically heated coil which surrounds and is in contact with the said tubular shell, to conduct heat to the 105 said shell and thence to the fluid within the said annular space, and an electric-insulating jacket which surrounds the heating coil.

JAY S. STROUSE.
